IRONING MACHINE

Charles A. Lindemann, Bridgeport, Conn., assignor to General Electric Company, a corporation of New York

Application January 11, 1938, Serial No. 184,405

8 Claims. (Cl. 68—60)

The present invention relates to ironing machines of the type having a shoe cooperating with a padded roll. The invention is particularly directed to a manually operable mechanism for moving the shoe relative to the roll. One use of such a mechanism is to provide an emergency release for relieving the pressure between the shoe and the roll. It can also be used to apply pressure between the roll and the shoe.

10 The object of my invention is to provide an improved mechanism in ironing machines for moving the shoe relative to the roll, and for a consideration of what I believe to be novel and my invention, attention is directed to the following description and the claims appended thereto.

In the accompanying drawings, Fig. 1 is a rear view of a rotary ironer embodying my invention; Fig. 2 is a sectional view taken on line 2—2 of Fig. 1, the parts being shown in the position in which the shoe is against the roll; Fig. 3 is a view similar to Fig. 2 the parts being shown in the position in which the shoe is farthest removed from the roll; Fig. 4 is a sectional view taken on line 4—4 of Fig. 2; Fig. 5 is a sectional view taken on line 5—5 of Fig. 3; Fig. 6 is a diagrammatic view showing a cover on the ironing machine; Fig. 7 is a sectional elevation showing a modification of the mechanism for moving the shoe relative to the roll, the parts being shown in the position in which the shoe is against the roll; Fig. 8 is a view similar to Fig. 7, the parts being shown in the position in which the shoe is farthest removed from the roll; and Fig. 9 is a detailed view of the upper end of the shoe supporting bracket.

Referring to the drawings, I have shown my invention applied to a rotary ironer comprising a suitably padded roll 1 which is supported and driven by mechanism contained within a housing 2 mounted on the top 3 of a suitable table. Fixed in a boss 4* in the housing and projecting therefrom along the roll is a tube 4 within which is journaled a rock shaft 5 by means of which a heated shoe 6 is moved toward and away from the roll. Constructions for oscillating the shaft 5 and for rotating and supporting the roll are well understood in the art and do not require illustration for the purposes of the present invention.

The shoe comprises an arcuate metal plate 7 heated by suitable electric heating elements, shown in elevation at 8 (Fig. 4), which are clamped to the rear surface of the plate 7 by means of clamping plate 9. Fixed to the rear

surface of the plate 7 are studs 10 by means of which a strut 11 is clamped to the rear side of the plate. Fixed to the intermediate portion of the strut is a U-shaped bracket 12 having sides 13 pivoted on a pin 14 extending between the side walls of an arm or bracket 15. The sides 13 fit in slots 16 in the side walls of the bracket 15. With this construction, the shoe is pivotally supported on the upper end of the arm 15. The rear side of the shoe is enclosed by a cover plate 17 fixed thereto in a manner not shown.

As shown in Fig. 5, one side wall of the arm 15 is pivoted on the tube 4 and the other side wall is pivoted on a bearing 18 integral with an arm 19 pivoted on the outer end of the tube 4 and extending within the space enclosed by the side and connecting walls of the arm 15. The arm 19 is splined on the outer end of the shaft 5 and is held against the outer end of the tube 4 by a coil spring 20 arranged between a seat 21 in the outer end of the arm 19 and a washer 22 held on the shaft by a snap ring 23. With this arrangement the bearing of the arm 19 on the tube serves as the outer bearing for the rock shaft 5 and the forces developed between the roll and the shoe are carried solely by the tube 4. The other end of the rock shaft 5 is journaled in a bearing 24. The rock shaft is oscillated by means of an arm 25 fixed to the end of the shaft within the housing 2.

The arm 19 has forked ends 26 between which is pivoted a pin 27. Rotatably and slidably carried in the pin 27 is a rod 28 around which is arranged a coil spring 29. The lower end of the coil spring bears on a seat 30 on a collar 31 which is slidable on the rod and is held by the spring against the upper side of the pin 27. The upper end of the spring 29 bears against a seat 32 on a nut 33 threaded on the upper end of the rod 28. Fixed to the lower end of the rod 28 is a knob 34 by means of which the rod may be turned to cause the nut 33 to be threaded up and down the rod and thereby change the compression of the spring 29. The knob 34 projects through the lower end of the bracket 15 and is, therefore, in a readily accessible position.

On the upper end of the rod 28 is a reduced portion 35 which is rotatable in a pin 36 carried between the forked ends 37 of a lever 38. The lever 38 is channel-shaped, as shown in Fig. 4, and the sides thereof fit between the side walls of the bracket 15 and are pivoted on the pin 14. The upper end of the reduced portion 35 of the rod 28 is held in the pin 36 by a snap ring 39.

As shown in Fig. 2 the lever 38, coil spring 29, and the associated parts comprise a toggle arranged between the pin 14 and the pin 27. When the parts are in the position shown in Fig. 2, the pin 36 is slightly to the right of a center line between the pins 14 and 27 and the toggle is accordingly in an over-center or locked position. In this position the lever ends 37 butt against a stop 41 on the bracket 15. The pressure exerted by the spring 29 tends to hold the toggle in the locked position.

The pressure between the roll and the shoe is transmitted to the toggle through the pin 14. This pressure is limited by the compression of the coil spring 29. Since the compression of the coil spring 29 is adjustable, the pressure between the roll and the shoe is accordingly adjustable. The minimum pressure between the roll and the shoe is obtained when the upward movement of the nut 33 is limited by the spacing sleeve 40 (as shown in Fig. 2). The maximum pressure is obtained when the downward movement of the nut 33 is stopped by the termination of the threads on the rod 28.

In the use of the ironing machine the thickness of the material being ironed and the thickness of the pad on the roll are subject to variation. If the roll and shoe were held in fixed relation there would, therefore, be a considerable variation in pressure. The above described construction minimises the variation in pressure. When an exceptionally thick piece of material is fed between the roll and the shoe, the shoe moves away from the roll, the arm 15 moving in a clockwise direction, as viewed in Fig. 2. Due to the location of the pin 27 at a point spaced rearwardly from the tube 4 the clockwise movement of the arm 15 tends to shorten the distance between the pins 14 and 27 thereby causing compression of the spring 29. The proportions are so chosen that the compression of the spring 29 is slight for the usual variations in thickness encountered during normal use. The pressure between the roll and the shoe, accordingly, remains substantially constant.

In the normal use of the ironing machine, the shoe is separated from the roll by moving the rock shaft 5 in a clockwise direction from the position shown in Fig. 2 to the position shown in Fig. 3 thereby moving the arm 19 to the position shown in Fig. 3. In this position the shoe is separated from the roll and the spring 29 accordingly expands until the shoulder 42 on the rod 28 strikes the lower side of the pin 27. In this position the spring is still compressed and the lever 38 is accordingly held against the stop 41. In other words, the toggle between the arm 19 and the bracket 15 is in its over-center or locked position.

Further separation of the shoe from the roll is obtained by pivoting the lever 38 in a clockwise direction, as viewed in Fig. 3, and thereby breaking the toggle connection to the shoe supporting arm 15. The lever 38 is pivoted by a hand lever 43 having an elongated slot 44 (Fig. 2) pivoted on a pin 45 fixed between the forked ends 46 of the lever 38. The lower end of the hand lever 43 has a notch 47 which fits over a tongue 48 on the lever 38. When the parts are in the position shown in Fig. 2 the hand lever 43 is rigid with the lever 38. When the hand lever is moved to the position shown in Fig. 3 the shoe is moved a substantial distance from the roll. The movement of the shoe is limited by the engagement of the lower end of the arm 15 and the rod 28

or of the upper end of the arm 15 and the lever 38. The shoe is normally inclined toward the roll, as shown in Fig. 3, the bracket 12 resting against the forked ends 37 of the lever 38. If desired, the shoe can be pivoted to a position in which the shoe faces upward. In this position the shoe can be conveniently cleaned and waxed and used for steaming.

By moving the hand lever 43 in a counterclockwise direction, as viewed in Fig. 3, the toggle connecting the lever 19 and the shoe supporting arm 15 can be returned to its locked position. The hand lever 43 can be used to release and apply the pressure between the roll and the shoe independent of the rock shaft 5.

By sliding the hand lever 43 to a position in which the notch 47 is clear of the tongue 48, the hand lever may be swung forward to the position shown in Fig. 6. This is of particular advantage when the ironer is enclosed by a cover 49, if the hinge connection between the levers 38 and 43 were not provided the vertical height of the cover would have to be increased. It is also an advantage in packing for shipment when no cover is supplied.

In Figs. 7, 8 and 9 is shown a modification which is in many respects identical with the previously described construction. Corresponding parts in the modification are indicated by the same reference characters. As in the previously described construction the rod 28 is slidably and rotatably carried in the pin 27 and the coil spring 29 is arranged between seats 30 and 32, respectively, on the collar 31 and nut 33. The compression of the spring 29 is varied by turning the rod 28 by means of the knob 34. The maximum compression of the spring is limited by the termination of the threads on the rod 28. The minimum compression is limited by a snap ring 40a.

The shoe is pivotally supported on the arm 15 by means of the pin 14 which extends through the side walls of the arm 15 and through the sides 13 of the bracket 12. A lever 50, which takes the place of the lever 38 in the previously described construction, is pivoted on the pin 14. Between the forked ends 51 of the lever 50 extends a link 52 having an elongated slot 53 fitting over the pin 14. The link 52 is connected to the upper end of the rod 28 by a swivel connection 54.

When the lever 50 is in the position, shown in Fig. 7, the lower ends 55 of the lever abut against the flat surfaces 56 on the upper end of the swivel connection 54. Since the abutting surfaces are flat the force exerted by the spring 29 resists the angular movement of the lever 50 from this position.

As in the previously described construction, variations in thickness of the material being ironed cause the shoe to be moved away from the roll compressing the spring 29. This decreases the variation in pressure during ironing.

When the shoe is moved away from the roll by the rock shaft 5 the pressure on the shoe is released. In this position the shoulder 42 on the rod 28 butts against the lower side of the pin 27. In this condition the spring 29 is still compressed and the lever 50 is accordingly held in line with the spring, as shown in Fig. 7.

The pressure between the roll and shoe may be released by pivoting the lever 50 through the hand lever 43 to the position shown in Fig. 8. In this position the pin 14 is near the bottom of the slot 53. This shortens the distance between the pins 14 and 27 and causes the arm 15 to be 78

5 moved in the direction to separate the shoe from the roll. By pivoting the lever 50 in a counter-clockwise direction from the position shown in Fig. 8, the lever may be returned to its normal

6 position. The return movement is made easier by the inclined surfaces 57 and 58 on the lower end of the lever and on the edge of the surface 56. From one aspect the ends 51 of the lever 50 serve as a cam.

10 What I claim as new and desire to secure by Letters Patent of the United States is:

11 1. In an ironer having a roll and a shoe, a support, an arm pivoted thereon carrying the shoe, a variable length connection between said arm and 15 said support comprising toggle links, one of which is of variable effective length and includes a spring exerting a longitudinal force toward the other link tending to hold the toggle in the locked position, and a stop carried by said arm for limiting movement of the toggle joint and thereby holding the links in the locked position.

16 2. In an ironer having a roll and a shoe, a rock shaft extending along the roll and having a part projecting rearwardly therefrom, an arm having its lower end pivoted on the axis of said shaft carrying the shoe on its upper end, a variable length connection between the projecting part of said shaft and said supporting arm including a member having its upper end connected to the upper end of said arm and having its lower end slideable in said projecting part, whereby said member slides through said projecting part as said arm pivots relative to the shaft away from the roll, and a spring resisting the sliding movement of 20 said member for yieldingly holding the arm and shaft in fixed relation whereby the shoe is moved toward and away from the roll by oscillation of the rock shaft.

25 3. In an ironer having a roll and a shoe, a support, a shoe supporting arm carrying the shoe at its upper end and pivoted on the support at its lower end, said arm having spaced side walls and a rear connecting wall, and a variable length connection between the upper end of the shoe supporting arm and the support at the rear of the pivot point of the shoe supporting arm, said connection being enclosed between the walls of said arm and including a spring exerting an upward force on the arm resisting movement of the shoe 30 away from the roll, and means including a rod extending through the support and having its lower end accessible at the lower end of said arm for adjusting the pressure of said spring.

35 4. In an ironer having a roll and a shoe, a support, a shoe supporting arm carrying the shoe at its upper end and pivoted on the support at its lower end, said arm having spaced side walls and a rear connecting wall, a manually operable lever pivoted on said arm between its side walls above 40 said support, and a spring between said side walls connected to said lever and to said support at a point at the rear of the pivotal axis of said

45 arm, said spring exerting an upward force on said arm resisting the movement of the shoe away from the roll.

5 5. In an ironer having a roll and a shoe, a support, a shoe supporting arm carrying the shoe at its upper end and pivoted on the support at its lower end, said arm having spaced side walls and a rear connecting wall, a variable length connection between said support and said arm comprising toggle links enclosed within said walls, one of which is a manually operable lever pivoted on said arm between its side walls above said support and the other of which is connected to the support at a point to the rear of the pivotal axis of said arm, said latter link including a 10 spring exerting an upward force on said arm resisting movement of the shoe away from the roll.

15 6. In an ironer having a roll and a shoe, a rock shaft extending along the roll and having a part projecting rearwardly therefrom, a shoe supporting arm carrying the shoe at its upper end and having its lower end pivoted on the axis of the shaft, said arm having spaced side walls and a rear connecting wall, toggle links enclosed within said walls and respectively pivoted on said arm above said projection and on said projection, one of said links including a spring exerting an upward force on said arm resisting movement of the shoe from the roll, and means including a 20 manually operable lever on said arm for breaking said toggle.

25 7. In an ironer having a roll and a shoe, a rock shaft extending along the roll and having a part projecting rearwardly therefrom, a shoe supporting arm carrying the shoe at its upper end and having its lower end pivoted on the axis of the shaft, said arm having spaced side walls and a rear connecting wall, a rod pivotally and slidably carried in said projecting part, a manually operable lever pivoted on said arm above the support and having a part below its pivot connected to said rod, said rod and lever being enclosed within said walls, and a compression spring urging said rod toward said lever whereby an upward force 30 is exerted on the shoe supporting arm through said lever resisting movement of the shoe from the roll.

35 8. In an ironer having a roll and a shoe, a rock shaft extending along the roll and having an operating arm extending rearwardly therefrom, a shoe supporting arm carrying the shoe at its upper end and pivoted on the rock shaft at its lower end, a link connected to said operating arm and extending upwardly therefrom, a second link pivoted on said supporting arm above the operating arm and having its lower end connected to said first link, one of said links including a spring exerting a force toward the connection between the links, and a handle on said second link for pivoting the link.

40 45 50 55 60 CHARLES A. LINDEMANN.
